[57] CLAIM

The ornamental design for a convertible toy vehicle, substantially as shown and described.

DESCRIPTION

FIG. 1 is a perspective view of a convertible toy showing my new design;

FIG. 2 is a rear elevational view thereof;

FIG. 3 is a right side elevational view thereof;

FIG. 4 is a bottom plan view thereof;

FIG. 5 is a left side elevational view of the design shown in FIGS. 1 through 4 in a converted condition, the side opposite being substantially a mirror image;

FIG. 6 is a top plan view thereof;

FIG. 7 is a front elevational view thereof;

FIG. 8 is a rear elevational view thereof; and,

FIG. 9 is a bottom plan view thereof.
